SMOKING PIPE

James B. Giern, Detroit, Mich., assignor of one-half to Anders P. Anholt, Detroit, Mich.

Application July 13, 1943, Serial No. 494,461

6 Claims. (Cl. 131—225)

The present invention, relates to improvements in smoking pipes and more particularly to a modified mouthpiece and stem structure therefor.

The primary object of the invention, is to provide a smoking pipe which is rugged in construction and composed of comparatively few breakable parts to prolong the life of the smoking pipe and prevent accidental breakage of the bowl and stem through strains or shocks when the pipe is carried in the pocket.

Another object of the invention, is to provide a smoking pipe of the above mentioned character, in which the smoke passage may be controlled to facilitate regulation of the volume of smoke passing from the bowl to the mouthpiece.

Another object of the invention, is to provide a smoking pipe as above set forth in which the mouthpiece is provided with an elongate tubular member having a perforated end projecting into the bottom of the bowl of the pipe in such a manner as to prevent clogging of the smoke passageway therein by tightly packed tobacco, and to enable the elongate tubular member to be given a partial rotation to free said perforations of any tobacco particles finding their way therein.

Another object of the invention, is to provide a smoking pipe of the above mentioned character, in which the elongate tubular element is formed of metal and is positioned in the bottom of the bowl in such a manner as to prevent burning out of the bottom wall of said bowl by excessive heat created through the burning tobacco.

Another object of the invention, is to provide a smoking pipe in which the stem of the bowl and mouthpiece are connected by a ferrule member carried by the mouthpiece and snugly fitting a thimble on the bowl stem, so as to allow partial rotation of the mouthpiece and elongate tubular member when freeing the apertures therein of tobacco particles and, at the same time, reinforce the connection so that the joint will be strengthened and made substantially rigid.

Another object of the invention, is to provide a smoking pipe in which the elongate tubular element carried by the mouthpiece is provided with a tapered end portion having a smoke passageway or port which is adapted to be regulated by being moved into and out of a tapered recess in the wall of the smoking pipe bowl, sliding movement of the ferrule and thimble connection being relied upon to facilitate the in and out movement of end of said elongate tubular member with the smoke passageway regulating recess in the wall of the smoking pipe.

Another object of the invention, is to provide

5 a smoking pipe of the above mentioned character in which the ferrule connecting the stem and mouthpiece is provided with a series of heat dissipating fins to facilitate cooling of the smoke drawn through the stem and mouthpiece from the bowl during use by a smoker.

10 Other objects and advantages of the invention, will become apparent during the course of the following description of the accompanying drawing wherein:

Figure 1 is a side elevational view of the smoking pipe illustrating the various parts thereof.

15 Figure 2 is a transverse cross sectional view taken on line 2—2 of Figure 1 looking in the direction of the arrows illustrating the ferrule joint between the pipe bowl stem and mouthpiece.

Figure 3 is a longitudinal cross sectional view taken on line 3—3 of Figure 2 looking in the direction of the arrows illustrating the structural parts of the smoking pipe in detail; and

20 Figure 4 is an exploded view of the smoking pipe showing the various parts in side elevation.

General description of the invention

25 The invention, broadly comprises a smoking pipe having a bowl with a tobacco receiving bore and a tubular stem portion in communication with said bore for the passage of smoke therethrough. The mouthpiece is provided with an elongate metal tube adapted to be inserted in said stem so that the perforated end of the metal tube will be disposed in the bottom portion of the tobacco receiving bore. A recess is formed in the wall of the tobacco receiving bore in alignment with the end of said elongate metal tube to receive the same, and thereby vary the smoke passageway therebetween when the mouthpiece is moved inwardly or outwardly with respect to the bowl or stem projecting therefrom. Further, the invention contemplates a ferrule and thimble connection between the stem and mouthpiece to form a snug fitting joint or connection between the same so that partial rotation of the mouthpiece relative to the stem may be permitted when manipulating the mouthpiece to either free the apertured end of the metal tube from tightly packed tobacco, or when adjusting the metal tube in the stem of the bowl to control the smoke passageway between the recess and ported end of said tube. The invention also provides a series of cooling fins on the ferrule to dissipate a large proportion of the heat in the smoke being drawn through the stem and mouthpiece to thereby insure a cool and enjoyable smoke by the user.

Detailed description

In the drawing, wherein for the purpose of illustrating the invention and wherein like reference characters will be employed to designate like parts throughout the same, the reference character 5 will generally be employed to designate a smoking pipe, including a bowl 6 having a stem portion 7 to which is attached the smoke tube or mouthpiece 8.

The bowl 6 is bulbous-shaped and is provided with a flat, self supporting bottom wall 9 continuous with the stem portion 7 to form a rest so that the pipe may be supported in an upright position when placed upon a surface, such as a table or the like. Formed in the bowl 6 is a tapered bore 10 which terminates at the bottom in a floor portion or well 11. The stem 7 is formed integral with the bowl 6 and is provided with a bore 12 extending laterally from, and communicating with, the tapered bore 10. The free end of the stem 7 is reduced to form a nipple portion 13, and said reduced nipple portion is fitted with a metal sleeve 14 adapted to be frictionally held in place, and said sleeve 14 extends from the shoulder 15 on the stem 7 to the end of the reduced nipple portion 13. An adhesive, or the like, may be inserted between the sleeve 14 and nipple 13 or, since the nipple 13 is formed of wood and the sleeve 14 of metal, said sleeve may be fitted thereon by a tight press fit in any suitable well known manner. The surface of the sleeve 14 is machined so as to provide a substantially true circular surface wall of uniform dimensions throughout its length.

The mouthpiece 8 is provided with a bore 16 extending from the bit portion 17 to the opposite end where it terminates in an enlarged bore 18 aligned with the bore 16. An elongate metal tube 19 has one of its ends received in said bore 18 so that the bore in the elongate tubular member 19 will align with the bore 16 of the mouthpiece 8. The free end of the elongate tubular member 19 is tapered as at 20 and is provided with a central aperture or opening 21 and similarly, a series of apertures 22 are formed on the peripheral portion of the elongate metal tube 19 adjacent the free end thereof so that when the tube is projected into the bowl 6 through the bore 12 the apertures 21 and 22 will provide smoke passageways between the tapered bore 10 of the bowl 6 and mouthpiece 8. Formed in the tapered wall 10 of the bowl 6 is a conical recess 23 in diametrically opposed relation to the bore 12 for receiving the tapered end 20 of the elongate metal tube 19, and facilitating the regulation of the aperture 21 by moving the tapered wall 20 toward and away from the recess 23. It is to be noted, that the internal diameter of the bore 12 is slightly larger than the outer diameter of the elongate metal tube 19 to relieve said stem 7 of undue stresses and strains imposed by forces accidentally exerted on the free end of the mouthpiece 8 and allow freedom of movement therebetween when the mouthpiece 8 and elongate metal tube 19 are slid longitudinally back and forth to space the tapered wall 20 the desired distance from the conical recess 23.

A metal ferrule generally designated by the reference character 24 is provided with a reduced bore 25 adapted to be received on the metal tube 19 and securely held thereon by being press fit or sweated in place. One end of the ferrule is enlarged as at 26 and is provided with an enlarged bore 27 coextensive with the bore 25, while

the opposite end is annularly flanged as at 28 so as to be pressed tightly against the shoulder 29 of the mouthpiece 8. The reduced portion 30 of the ferrule 24, between the enlarged portion 26 and annular flange 28, is provided with a series of circular heat dissipating fins 31 to cool the smoke passing from the bowl 10, elongate metal tube 19 and the area or zone adjacent the inner end of the mouthpiece 8. The cooling fins 31 are formed integral with the reduced portion 30 of the ferrule.

After the metal ferrule 24 is thus fitted and secured to the elongate metal tube 19, the free end of the tube is passed through the bore 12 so as to project into the tapered bore 10 in spaced relation to the floor or well 11, with the conical end 20 spaced a sufficient distance from the conical recess 23 to permit the passage of smoke from the bowl to the mouthpiece 8. When the metal tube 19 is thus inserted, the finely machined enlarged bore 27 will snugly fit upon the sleeve 14 as shown in Figure 3 and thereby establish a substantially rigid joint between the stem 7 and mouthpiece 8. It is to be understood that the mating surfaces of the sleeve 14 and enlarged bore 27 are machined so as to provide a snug sliding frictional fit in order that the mouthpiece 8 may be partially rotated and thereby cause partial rotation of the tube 19 so as to shift the apertures 20 relating to the tobacco packed in the tapered bore 10 of the bowl to free the apertures 22 from the particles of tobacco packed therearound.

It is to be noted that the metal tube 19 projects into the bore 10 and extends the entire length of the floor or well 11 so as to provide suitable protection for the reduced portion of the bowl between the flat self supporting surface 9 and the floor 11, thereby preventing burning out of said wall which is formed comparatively thin due to the removal of the bottom portion of the bowl to form said self-supporting surface 9.

Operation

45 In use, the parts are assembled as shown in Figures 1 to 3 inclusive and the smoker may fill the tapered bore 10 with tobacco and pack the same by pressing the same downwardly as usual. After the bore of the bowl has thus been filled, the 50 mouthpiece 8 may be turned to the right or left so as to rotate the free end of the metal tube 19 to and fro, and thereby free the apertures 20 of tobacco particles finding their way therein. The tobacco filling in the bowl is then ignited by the 55 application of a lighted splint or match, and the pipe is smoked by the user in the conventional manner. Should the smoker desire to increase or decrease the amount of smoke passing through the tube 19 and mouthpiece 8, he grasps the 60 mouthpiece 8 while holding the bowl in the other hand and slides the mouthpiece and metal tube inwardly or outwardly with respect to the bowl 6. During such sliding movement, the finely machined mating surfaces 14 and 27 of the sleeve 65 and enlarged bore respectively move relative to one another without destroying the connection between the ferrule and stem for preventing escape of smoke or air therebetween.

It is to be understood that the form of the invention herewith shown and described is to be taken as a preferred embodiment of the same and that various changes in the shape, size and arrangement of parts may be resorted to without departing from the spirit of the invention or the 75 scope of the subjoined claims.

What I claim is:

1. In a smoking pipe, a bowl having a bore for receiving tobacco, a stem formed on the bowl provided with a passageway communicating with said bore, a mouthpiece detachably secured to the stem, a tubular member carried by the mouthpiece extending through said passageway and into the bore of the bowl in spaced relation to the walls thereof, and a thimble secured to said tubular member having cooling fins at one end and a ferrule at the other end for snugly fitting the free end of said stem to permit endwise sliding movement of the mouthpiece and tubular member whereby the distance between the end of said tubular member and wall of said bore may be regulated.
2. In a smoking pipe, a bowl having a bore for receiving tobacco, a stem formed on the bowl provided with a passageway communicating with said bore, a mouthpiece detachably secured to the stem, a tubular member carried by the mouthpiece extending through said passageway and into the bore of the bowl in spaced relation to the walls thereof, and a connector secured on said tubular member having a series of annular cooling fins at one end and a ferrule at the opposite end for snugly and slidably receiving the free end of said stem to permit endwise sliding movement of the mouthpiece and tubular member whereby the distance between the end of said tubular member and wall of said bore may be regulated.
3. In a smoking pipe, a bowl having a tobacco receiving bore, a stem formed on the bowl provided with a passageway communicating with said bore, a mouthpiece detachably secured to the stem, a tubular member carried by the mouthpiece extending through said passageway and into the bore of the bowl in spaced relation to the walls thereof, a sleeve secured on a reduced end portion of said stem and a ferrule on said tubular member having a bore for snugly receiving said sleeve to permit endwise sliding movement of the mouthpiece and tubular member whereby the distance between the end of said tubular member and wall of said bore may be regulated.
4. In a smoking pipe, a bowl having a tobacco receiving bore and stem portion therefor, a mouthpiece slidably and detachably connected to said stem, an elongate tubular member secured to the mouthpiece extending through the stem and projecting into the bore of the bowl, said tubular member having a conical ported end adapted to be presented to a correspondingly shaped recess in the bore, said mouthpiece being slidable endwise to regulate the distance between one wall of said bore and the inner end of said tubular member to control the passage of smoke through said tubular member, a sleeve having a relatively smooth machined surface fixed to a reduced end portion of the stem and a ferrule secured to the elongated tubular member having a bore with an internal smooth machined surface for receiving said sleeve to provide a snug fit therebetween to permit endwise movement of said mouthpiece and tubular member when regulating said smoke passageway.
5. In a smoking pipe, a bowl having a bore for receiving tobacco, a stem formed on the bowl provided with a passageway communicating with said bore, a mouthpiece detachably secured to the stem, a tubular member carried by the mouthpiece extending through said passageway and into the bore of the bowl in spaced relation to the walls thereof, a sleeve fitted on a reduced portion of said stem having a relatively smooth machined surface, and a metal ferrule having a series of cooling fins at one end mounted on said tubular member and a bore in the other end of the ferrule having an interior smooth surface for receiving the sleeve and providing a snug fit therebetween to permit endwise sliding movement of the mouthpiece and tubular member whereby the distance between the end of said tubular member and wall of said bore may be regulated.
6. In a smoking pipe, a bowl having a bore for receiving tobacco, a stem formed on the bowl provided with a passageway communicating with said bore, a mouthpiece detachably secured to the stem, a tubular member carried by the mouthpiece extending through said passageway and into the bore of the bowl in spaced relation to the walls thereof, a sleeve fitted on said stem having a relatively smooth finely machined surface, a ferrule on said tubular member having a smooth walled recess for receiving said sleeve to form a snug fit between the mouthpiece and stem to permit endwise sliding movement of the mouthpiece and tubular member whereby the distance between the end of said tubular member and wall of said bore may be regulated and a series of cooling flanges on said ferrule to cool the smoke passing therethrough.

JAMES B. GIERN.
